CLAIM

The ornamental design for a paint spray gun manifold
attachment, as shown and described.

DESCRIPTION

FIG. 1 is a perspective view of a paint spray gun manifold
attachment, showing my new design;

FIG. 2 is a top plan view thereof, the bottom plan being
a mirror image;

FIG. 3 is an elevational view of one side thereof, the
opposite side being a mirror image; and,

FIG. 4 is an elevational view of one end thereof, the
opposite end being a mirror image.
